UNITED STATES PATENT OFFICE.

GEORGE L. SCHOFIELD, OF KANSAS CITY, MISSOURI.

ROTARY VALVE FOR INTERNAL-COMBUSTION ENGINES.

1,222,681.

Specification of Letters Patent. Patented Apr. 17, 1917.

Application filed March 18, 1916. Serial No. 85,069.

To all whom it may concern:

Be it known that I, GEORGE L. SCHOFIELD, a citizen of the United States, residing at Kansas City, in the county of Jackson and State of Missouri, have invented certain new and useful Improvements in Rotary Valves for Internal-Combustion Engines; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to rotary valve mechanism for internal combustion engines, and has for its principal object to effectually lubricate the rotary valve part.

In accomplishing this object of the invention I have provided improved details of structure, the preferred forms of which are illustrated in the accompanying drawings, wherein:

Figure I is a central vertical section of a four cylinder internal combustion engine embodying my improvements.

Fig. II is an end view of the same, parts of the chain belt being broken away for better illustration.

Fig. III is a transverse vertical section of one of the cylinders and valve seats.

Fig. IV is a plan view of the engine, particularly illustrating the valve mechanism.

Fig. V is a horizontal section through the rotary valve members.

Fig. VI is a detail perspective view of a stationary valve cup.

Fig. VII is a similar view of the rotary valve.

Fig. VIII is a vertical section on the line VIII—VIII, Fig. I, showing the oil pumps and manifold connection.

Fig. IX is a vertical section on the line IX—IX, Fig. IV, illustrating the check valve between the feed conduit and oil chamber.

Referring more in detail to the drawings:

1 designates the crank case, and 2, 3 and 4 respectively the cylinder, valve and valve drive shaft housings of an internal combustion engine, here shown to be of the vertical type, and wherein the cylinders are paired for a purpose presently described.

Each of the cylinders 6, 6', etc., extends continuously through the housing 2, opening at its lower end to the crank case 1 and at its outer end into a valve cap 7 or 7', etc., which caps are preferably formed integrally with the housing 3 and are of less diameter than the cylinders to form shoulders 9 at the upper ends of the cylinders.

Located in each of the valve caps is a cup 11 having a flange 12 at its inner end located within the adjacent cylinder and bearing against the shoulder 9, and secured to said shoulder by bolts 13 so that the cup is held rigidly in place and against rotation.

The cup is also provided with a shoulder 14 forming a seat against the corner of the valve cap, and with a second shoulder 15, whereby the body of the valve cup is inset from the valve cap to form an annular chamber 16 between the cap and cup. The outer end of the valve cup is closed and is spaced from the outer end of the cap 7 to form a chamber 18 for containing the end of the rotary valve presently described, and forming an oil chamber from which the valve parts may be lubricated.

The valve cup is provided with an intake port 20, an exhaust port 21 and a spark port 22, which register with relative intake, exhaust and spark ports 24, 25 and 26 in the valve housing; the intake and exhaust ports in the valve cup being preferably extended longitudinally of the cup, and the spark port transversely thereof, for the reason that the area within which the intake and exhaust ports must be confined is small, and in order to admit and exhaust the charges rapidly it is necessary to have the greatest possible opening in the valve cup for a limited time period, which result can be secured better with the arrangement described than with a long transverse port that would require a longer timing communication with the intake and exhaust manifolds.

The spark port, however, does not need the extended area but should have a longer time communication between the spark plug and interior of the valve in order to insure proper admission of the spark, and by elongating the spark port in the valve cup, impact of explosion of charges within the cylinder will be distributed evenly through the several cup ports against the rotary valve presently described, and thereby avoid un-

even pressures on the valve that might tend to misform the valve and eventually interfere with its proper operation.

5 The rotary valve comprises an inverted cup-shaped body 28, the rim of which fits snugly within the annular space 16 between the valve cup and the valve cap, and has a single port 29 that is adapted for movement successively across the intake, spark and exhaust ports in the valve cup and cap, so that 10 communication is established at proper intervals between the intake manifold, the spark plug and exhaust manifold with the intake, spark and exhaust ports of the valve cup.

15 The base of the valve is solid and fits snugly over the solid base of the valve cup, the valve base being spaced from the end of the valve cap by a boss 30 in order to 20 provide space between the valve base and bottom of the cap for containing lubricant for the valve.

25 Fixed to the valve base, and extending through the boss 30, is a shaft 31 that is journaled in the base of the valve cap and in the top of the valve housing, and fixed to 30 said shaft is a beveled gear wheel 33 or 33' that meshes with a beveled gear wheel 34 or 34' on the valve drive shaft 35, which is 35 journaled in bearings 36 within the shaft housing and extends through one end of the housing. The beveled gear wheels 33-33' and 34-34' are identical except in the mounting of the driving wheels 34-34' on the shaft 35, the difference being that the gear wheels for each pair of cylinders face oppositely, so that the gear wheels 33-33', and the valves operatively connected therewith, are turned in opposite directions.

40 With this arrangement, the timing of the functions of the valves may be accomplished as readily as were the valves driven in the same direction, but it is possible to concentrate and consolidate the intake manifolds, 45 as the intake ports of the paired cylinders are located closely adjacent each other (Fig. V) making it possible to run the main intake manifold 38 close to the point of intake to the cylinders, and there provide the branches 50 39-39' to the respective intake ports. The exhaust ports may empty into the exhaust manifold 40 through the pipes 41-41' in the usual manner.

55 In order to effectually lubricate the valves, I provide each rotary valve with a port 43 adjacent the spacing boss 30 through which oil from the chamber 18 may flow into contact with the top of the stationary valve cup 11, and provide the top of the valve cup with a groove 44 that extends to the edge of the cup and communicates with a groove 45 in the outer surface of the cup that is preferably spiraled forwardly relative to the direction of travel of the valve, 60 so that oil passing through the port 43 into

the groove 44 is forced along the groove and down the same to the base of the cup, in order to effectually lubricate the entire inner surface of the valve that contacts the outer surface of the valve cup.

70 I also provide for lubricating the valve at its outside, or at its point of contact with the valve cap, by providing the valve with a reversely extending circumferential groove 47.

75 It is apparent that with the forwardly directed groove in the stationary valve cup, forward movement of the valve will force oil along the groove, and with the rearwardly directed groove in the outer face of the oil cup, forward movement of the valve 80 will force oil rearwardly through its groove, thereby effecting lubrication of both the inner and outer surfaces of the rotary valve.

85 In order to insure supply of lubricant within the cap chamber, I provide each chamber with an intake conduit 49 and an outlet conduit 50, the outlet conduit comprising a hollow bolt that is extended through the bottom of the valve shaft housing and the top of the valve housing, and communicates with the chamber 18.

90 The intake conduit opens outwardly through a port 48 near the head of the bolt into an annular channel 49' and leading from said chamber is a bore 52' that communicates with a tube 52 that, in turn, communicates with a manifold 53, which, in turn, communicates with a pump chamber 54 in the valve shaft housing through a pipe 55. The second conduit 50, having 100 communication with the oil chamber in the valve cap, also comprises a hollow bolt, one end of which opens to the oil chamber and the other to the interior of the valve drive shaft housing. The bolt shaped conduits 105 also serve to rigidly connect the valve and valve drive shaft housings and obviate the necessity for extra bolts.

110 The drive shaft 35 carries an eccentric 57 that operates a pump piston 58 in the chamber 54, and which lifts above the intake port 59 through which oil may be delivered from the valve drive shaft housing, which also serves as an oil reservoir, to the pump chamber, so that when the engine is 115 in operation the pump will take oil from the oil reservoir, force the same through the oil manifold 53 into the several conduits 49, and thence into the chambers 18 of the valve caps, where the oil may pass to the rotary valve as heretofore described. The circulation through the valve caps is continued 120 through the return conduits 50 to the oil reservoir in the valve drive shaft housing, from which the oil is originally pumped, so that oil is continuously circulated from the valve shaft housing, through the valve cap chambers, and back to the housing, thereby insuring the constant lubrication of all of the 125 rotary valves, the intake conduit 49 being of 130

greater capacity than the return or outlet conduit 50 to insure constant pressure in the oil chamber in the valve cap.

By opening the conduit 49' to near the bottom of the pump chamber, when the pump piston is raised to take in oil from the oil reservoir, the back check valve is closed and a vacuum created in the pump chamber that tends to draw in oil from the reservoir when the inlet port 58' is uncovered by the piston.

To prevent any backward flow of the oil to the pump chamber, I provide the conduit 55, which leads from the pump to the manifold 53, with a ball check 60 which is held against a seat 61 by a coil spring 62, and to prevent backflow from the valve chamber I provide the intake conduits 52, which lead from the manifold 53 to the various valve chambers, with ball checks 63 (Fig. IX) which are held against seats 64 by coil springs 65.

By so arranging the check valves, oil pumped into the manifold 53 will be held against return to the pump and will be forced through the conduit to the valve chambers; the checks 53 preventing any back flow of unequal pressure within the several valve chambers 18.

30 The valve drive shaft 35 may be operated in any suitable manner, but is preferably driven from a chain belt 66 that runs through a casing 67 and over a sprocket wheel 68 on the end of the valve shaft and over a sprocket wheel 69 on the end of the crank shaft 70, the arrangement of the drive being such that the valve drive shaft makes one revolution for two revolutions of the crank shaft.

40 The crank shaft is rotatably mounted within the crank case 1, which preferably contains oil, so that the pistons 71 of the several engine cylinders are splashed when they are driven by the crank shaft, through the piston rods 72.

Assuming the parts to be constructed and assembled as described, when the engine is in operation, the crank shaft is rotated and rotates the valve drive shaft. The valve drive shaft operates the gear wheels 34-34', etc., so that the paired gear wheels operate in opposite directions to drive the rotary valves accordingly. As the rotary valves move about the cups the single port in each rotary valve successively uncovers the intake, spark and exhaust ports in the stationary valve cup, so that communication is established with the intake supply, with the spark plug, and with the exhaust conduit. When the spark is admitted to the cylinder, the charge is exploded and the explosion produces an impact in all directions, which passing through the several ports in the stationary valve cup strikes the rotary valve member.

If the impact occurred at the same and a single point on the valve member at each revolution, the valve would be subject to unequal pressures, but by providing the balancing ports the impact is the same at the three balanced positions, so that strain on the rotary valve member is balanced.

During the operation of the engine, the valve drive shaft revolves constantly and operates the lubricant pump, which forces oil through the intake conduits to the lubricant chamber in each valve cap. This lubricant passes through the chamber to the grooves in the valve and valve cup, and rotary movement of the valve forces the lubricant along the grooves to effect complete lubrication of the contacting parts; the pump meanwhile continuing circulation through the cap chambers to insure a constant supply of oil.

With the arrangement described, all of the valve caps and the cylinders may be water-jacketed and a more compact arrangement of the parts effected, owing to the fact that the intakes for the paired cylinders are closely adjacent each other; this close arrangement being effected without necessitating any greater spacing of the exhaust conduits.

By reversing the arrangement of the paired valve members, the strain and tension of the valves is balanced, with the result that a steadier, more stable, and less racking effect is produced upon the operation of the engine.

Having thus described my invention, what I claim as new therein, and desire to secure by Letters-Patent, is:—

1. In an engine, a rotary valve, an inclosure for the valve, a valve operating shaft, an inclosure for said shaft also serving as a lubricant container, separate conduits connecting the valve inclosure with the shaft housing, one comprising an intake and the other an outlet, the outlet being of less capacity than the inlet, and means for forcing oil from the shaft housing to the valve inclosure, whereby pressure of the oil is maintained within the inclosure because of the lesser capacity of the outlet conduit.

2. In an engine, a plurality of individual valve housings, a valve rotatably mounted in each housing, a lubricant container, an intake conduit leading to each valve housing, a manifold in communication with the oil container and having connection with each of the said intake conduits, a pump for drawing oil from the container and forcing the same into the manifold, and an individual outlet conduit for each valve housing opening to the oil container whereby oil is circulated through the container and all of said valve housings.

3. In an engine, a plurality of individual valve housings, a valve rotatably mounted

- in each housing, a lubricant container, an intake conduit leading to each valve housing, a manifold in communication with the oil container and having connection with 5 each of the said intake conduits, a pump for drawing oil from the container and forcing the same into the manifold, and an individual outlet conduit for each valve housing opening to the oil container whereby oil is 10 circulated through the container and all of said valve housings, all of the outlet conduits being of lesser capacity than the respective intake conduits, whereby oil is maintained under pressure in the several 15 valve housings.
4. In an engine, a plurality of cylinders, a valve for each cylinder, an inclosure for each valve, an oil reservoir, a manifold in communication with said reservoir, feeding conduits leading from the manifold to the respective inclosures, conduits leading from the respective inclosures to the reservoir, and a pump for forcing oil from the reservoir to the manifold.
- 20 5. In an engine, a plurality of cylinders, a valve for each cylinder, an inclosure for each valve, an oil reservoir, a manifold in communication with said reservoir, feeding conduits leading from the manifold to the respective inclosures, conduits leading from the respective inclosures to the reservoir, and a pump for forcing oil from the reservoir to the manifold, and a back check valve in each feeding conduit.
6. In an engine, a plurality of cylinders, a valve cap for each cylinder, a rotary valve in each cap, a valve shaft housing, a shaft for each valve projected into said housing, a single actuating shaft in the housing, bevel gear wheels on the several valve shafts, 40 a bevel gear wheel on the single shaft meshing with each of said several gear wheels, a manifold in communication with the valve shaft housing, a conduit leading from the manifold to each of the valve caps, a pump 45 for forcing oil from the housing to the manifold, and a conduit leading from each valve cap to the housing.
7. In an engine, a cylinder, a valve for the cylinder, a housing for the valve, an oil reservoir, and a hollow bolt securing the oil reservoir to the valve housing and serving as a conduit between the valve housing and oil reservoir.

In testimony whereof I affix my signature. 55
GEORGE L. SCHOFIELD.
